UNITED STATES PATENT OFFICE.

CHARLES SCHEIDL, OF PHOENIXVILLE, PENNSYLVANIA, ASSIGNOR TO THE PHOENIX BRIDGE COMPANY, OF SAME PLACE.

SUBWAY.

SPECIFICATION forming part of Letters Patent No. 361,086, dated April 12, 1887.

Application filed January 26, 1887. Serial No. 225,555. (No modcl.)

To all whom it may concern:

Be it known that I, CHARLES SCHEIDL, a citizen of the United States, residing in Phoenixville, Chester county, Pennsylvania, have 5 invented an Improved Subway, of which the following is a specification.

The object of my invention is to provide a subway which may be quickly and economically constructed and yet be of great strength; 10 and this object I attain by constructing the subway of a series of independent self-contained metallic frames arranged at intervals and connected or united by masonry or metallic walls, as hereinafter fully set forth.

15 In the accompanying drawings, Figure 1 is a transverse section on the line 1 2, Fig. 3, of a subway constructed in accordance with my invention. Fig. 2 is a longitudinal section on the line 3 4, Fig. 1, of a portion of the same. 20 Fig. 3 is a sectional plan view on the line 5 6, Fig. 1, also of a part of the subway; and Fig. 4 is a perspective view of one of the self-contained metallic frames used in carrying out my invention.

25 My improved subway may be used for an underground street, or street or steam rail-ways, and for the conveyance of water, gas, or steam, or pneumatic mains or pipes, or for electrical conductors, either in the form of in- 30 dividual wires or cables.

In the drawings I have shown a subway constructed for the accommodation of two rail-way-tracks or equivalent passage-ways, A A', and at one side a part, B, for the conveyance 35 of electrical conductors and mains and pipes for water, gas, steam, or pneumatic purposes. I do not, however, wish to limit myself to this or any other particular arrangement of pas- 40 sage-ways in the conduit.

45 In the erection of my conduit I build a series of separate self-contained frames, substantially as illustrated in Fig. 4, each consisting, essentially, of two side columns, C C', a top cross-beam, D, and a bottom connecting-beam, D', and between the end columns may be one or more intermediate supporting-columns, E, depending on the width and desired strength 45 of the subway. In the present instance I have shown two such columns in each frame. The 50 beams and columns may be of channel or angle iron, or any other desired or convenient shape

or style. That is a detail which does not enter into the essence of my invention. The metallic frames thus constructed of the requisite size are placed in the subway at suitable intervals apart—say five feet—on a suitable foundation, f', of cement or other convenient material, as illustrated in Figs. 2 and 3. The frames thus arranged are connected at the sides and top by walls of masonry or iron-work to support the pressure of the earth and overhead traffic. In the present instance I have illustrated the side columns, C C', of adjacent beams as united by walls of masonry, brick arches F being built in between the upright beams, 65 Figs. 1 and 3, (with a cement filling at the back,) to withstand the pressure of the earth. The top wall or roof is formed in the present instance of metal, a series of plates or bars, G, being laid longitudinally side by side along 70 the tops of the cross-beams of the metallic frames and secured to the latter, Figs. 1 and 2. On this roof is laid the cement or other foundation for the roadway above. Instead of this metallic form of roof, it may be constructed of 75 masonry with brick arches connecting the metallic frames, as the above-described side walls are constructed, and as indicated by dotted lines at the upper left-hand side of Fig. 2; and on the other hand the side walls may be formed 80 of the channel-bars G, secured horizontally to the upright end beams. If desired, brick arches, similar to the arches F, forming the side walls of the subway, may be employed in forming the bottom thereof, as indicated by dotted lines 85 in Fig. 2. In such case the form of the beams D' would have to be changed, as also indicated by dotted lines in that figure.

If desired, the frames may be further connected with each other by braces e, running 90 from the columns E of one frame to the corresponding columns of the adjacent frames. In Fig. 2 I have shown the frames thus braced in sets of three. The parts of the frames which are in the part of the subway for the accom- 95 modication of the gas and water pipes and mains, electrical conductors, &c., may be provided with suitable cross-pieces, p p, for the support of the various mains, pipes, conductors, &c.

The above-described form of subway, it will 100 be evident, can be much more quickly and economically constructed, and is much stronger

than one having independent columns and arches.

I claim as my invention—

1. A subway composed of a series of self-contained frames or columns and beams, with side and top walls of masonry or metal connecting the several frames, substantially as set forth.

2. A subway composed of a series of self-contained frames of columns and beams, with side walls of masonry and top wall or roof of metal uniting the frames, substantially as set forth.

3. The combination of frames composed of top and bottom beams and end and intermediate columns, with side and top walls of ma-

sonry or metal connecting the several frames, the whole forming a subway, substantially as described.

4. The combination of frames composed of top and bottom beams and end and intermediate columns, with side walls of masonry and top wall of metal bars uniting the several frames, all substantially as set forth.

In testimony whereof I have signed my name to this specification in the presence of two subscribing witnesses.

CHARLES SCHEIDL.
